US00D876961S

(12) **United States Design Patent** (10) Patent No.: **US D876,961 S**
(45) Date of Patent: **** Mar. 3, 2020**

(54) **CONTAINER**

(71) Applicant: **IDEXX Laboratories, Inc.**, Westbrook, ME (US)

(72) Inventors: **Michael Fletcher**, Portland, ME (US); **David L. Connolly**, Eliot, ME (US); **Anne Leavitt**, Gorham, ME (US); **Matthew M. Furtney**, Freeport, ME (US); **Daniel O'Sullivan**, Mont Vernon, NH (US); **Christopher Labak**, Brookline, NH (US); **Christopher Aiston**, Mont Vernon, NH (US)

(73) Assignee: **IDEXX LABORATORIES, INC.**, Westbrook, ME (US)

(**) Term: **15 Years**

(21) Appl. No.: **29/686,044**

(22) Filed: **Apr. 2, 2019**

(57) **CLAIM**

The ornamental design for a container, as shown and described.

DESCRIPTION

FIG. 1 is a perspective view of a container in accordance with the present design;

FIG. 2 is a bottom plan view thereof;

FIG. 3 is a top plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines shown in the drawings illustrate portions of the container that form no part of the claimed design.
